(57) **CLAIM**

The ornamental design for a convertible sofa bed with arms that convert into foot rests, as shown and described.

DESCRIPTION

FIG. 1 is a front perspective view of the convertible sofa bed being in a sofa position;

FIG. 2 is a front view of the convertible sofa bed being in a sofa position;

FIG. 3 is a side view of the convertible sofa bed being in a sofa position;

FIG. 4 is a front perspective view of the convertible sofa bed with one of the arms being between an arm position and foot rest position;

FIG. 5 is a front perspective view of the convertible sofa bed with one of the arms being between an arm position and foot rest position;

FIG. 6 is a front perspective view of the convertible sofa bed with one of the arms being in a foot rest position;

FIG. 7 is a front view of the convertible sofa bed with both of the arms being in a foot rest position;

FIG. 8 is a top view of the convertible sofa bed being in a bed position with both of the arms being in a foot rest position;

FIG. 9 is a side view of the convertible sofa bed being in a sofa position with at least one of the arms being in a foot rest position;

FIG. 10 is a side view of the convertible sofa bed with the seat back being between a sofa and bed position and with at least one of the arms being in a foot rest position;

FIG. 11 is a side view of the convertible sofa bed with the seat back being between a sofa and bed position and with at least one of the arms being in a foot rest position;

FIG. 12 is a side view of the convertible sofa bed with the seat back being between a sofa and bed position and with at least one of the arms being in a foot rest position;

FIG. 13 is a side view of the convertible sofa bed being in a bed position with at least one of the arms being in a foot rest position;

FIG. 14 is a side view of the convertible sofa bed with the seat back being split into sofa and bed positions and with at least one of the arms being in a foot rest position;

FIG. 15 is a side view of the convertible sofa bed with the seat back being split into sofa and bed positions and with at least one of the arms being in a foot rest position;

FIG. 16 is a back view of the convertible sofa bed being in a sofa position; and, FIG. 17 is a bottom view of the convertible sofa bed being in a bed position and with both arms in the foot rest position.

The broken lines shown in the drawings are for illustrative purposes only and form no part of the claimed design.
